COUPLING CIRCUIT ARRANGEMENT FOR
ULTRA-SHORT WAVES

Kurt Schlesinger, Berlin, Germany, assignor, by
mesne assignments, to Loewe Radio, Inc., a
corporation of New York

Application July 23, 1938, Serial No. 220,876
In Germany October 26, 1937

1 Claim. (Cl. 178—44)

The present invention relates to coupling circuit arrangements for the transmission of broad frequency bands such as used in television art. It is known that in performing amplification by way of oscillatory circuits the ratio between self-induction and capacity

$$\left(\frac{L}{C}\right)$$

must be selected to be as large as possible for obtaining a frequency range which is as large as possible. It is also known that the effective working resistance of a tuned anode or grid circuit cannot be greater than one-half of the impedance of the capacity of the circuit in respect of the highest modulating frequency (maximum image frequency) to be transmitted. These two reasons accordingly resulted at an early date in the so-called variometer tuning of amplifiers, in which, therefore, the carrier wave was adjusted by variation of the self-induction in conjunction with the associated capacities of the circuit system and the tube.

The amplifiers which have become known for the ultra-short carrier waves employed for television purposes relate throughout to single-circuit couplings between two tubes. The resulting frequency curve is accordingly the usual resonance curve of "bell" form with a considerable drop in the case of higher frequencies. In a plurality of successive amplifying stages the frequency drop is naturally additive. It must accordingly be corrected later by networks, possibly after the rectification. In the known arrangements the tuning is performed by means of small rotating plate condensers. There is not achieved in this way an optimum amplification, as the circuit capacity is not limited to the smallest possible value, viz., the tube- and stray-capacities, but is increased by the tuning condenser.

In accordance with the present invention a circuit arrangement for coupling broad frequency bands modulated upon short or ultra-short waves is claimed which avoids the stated disadvantages and produces the greatest degree of efficiency on the basis of the two aspects referred to above.

The drawing shows an exemplary embodiment of the circuit arrangement in accordance with the invention. Therein the amplifier tubes 1 and 2 are coupled by means of two tunable circuits producing a band-filter effect. The two circuits comprise pure self-inductances 3 and 4 and a pair of coupling coils 5 and 6 in series connection. The two self-inductances 3 and 4 are completely balanced out in relation to one another by a sheet-metal screen 1. The effective coupling

which assures the transmission is accordingly effected only between the coils 5 and 6. The tuning of the grid and anode circuits to the carrier wave takes place in accordance with the invention by the fact that in each of the tuning coils 3 and 4, which represent the greater part of the self-inductance of the coupling circuit, there is provided a metallic cylinder consisting of a good conductive material (for example copper tube) 3a or 4a. In this connection it is to be observed that the diameter of the tuning cylinder differs as little as possible from the diameter of the winding of the coils 3 and 4. There is accordingly employed merely a very thin insulating layer between the two and a comparatively thin wire for the winding. With a dimensioning of 20:21 mm. with respect to the diameter of the tuning cylinder and coils there can be obtained in the wholly inserted position and in the wholly withdrawn position, wavelength variations of 1:2.

The direction of winding of the pair of coupling coils 5/6 is so chosen that the influence coupling between the two windings assists the coupling effect via the stray capacity 8. In this case the width of band of the amplification remains practically constant over the entire tuning range of approximately an octave. The width of band itself is adjusted by the degree of coupling between 5 and 6. In the case of comparatively strong couplings there result the two known resonance bulges of the coupling waves. These must then be flattened out by resistances 9 and 10 in the anode and grid circuits. The resistances are preferably selected not to be greater than the resistance value

$$\frac{1}{\omega C}$$

of the appendant capacities in the case of the highest frequency of the picture to be transmitted. It has been found that the use of special tubes with particularly small loss capacities does not provide any appreciable advantage as compared with the use of normal radio screening-grid tubes—the latter, however, with very considerable slope. In the latter case the gain in slope compensates the capacitative losses. The capacities can be kept below 15 cm., and this results upon the transmission of band widths of the order of 2 megacycles a resistance value of approximately 2,000 ohms with respect to the damping resistances 9 and 10. The total amplification degree of an arrangement of this kind can reach 8 or more, with a carrier wave of between 30 and 60 megacycles.

In the practical embodiment of such a circuit

arrangement which may be called a vario-band-filter the two tuning cylinders 4a and 3a can be coupled together and pushed in simultaneously by the same actuating means. In order correctly to tune the natural wavelength one or both of the tuning coils 3 or 4 can be furnished with a preadjustment relative to the edge of the tuning cylinder. The width of band is adjusted to the desired value by a single adjustment of the coupling coil value 5 and 6. The pair of coupling coils 5/6 must naturally be screened inductively and capacitatively against the tuning coils 3 and 4. This also applies to the two coils 3 and 4 in relation to one another. The entire coupling element is finally placed in a common screen-casing.

If there are to be coupled with a vario-band filter of this kind low-resistance circuits, i. e., aerial or transmission leads, it is possible either to couple the low-resistance input inductively with the primary coil 3 or to tap the primary coil to the extent of the optimum coupling. It has been found that the coupling windings can be applied, on the tunable coil portion, together with the short-circuit cylinder, without the coupling effect being too greatly weakened upon the wave shortening.

I claim:

An amplifier system comprising a first thermionic tube and a second thermionic tube, each of said tubes having an input and an output circuit, means for applying signals for amplification to the input circuit of the first tube, a pair of inductance elements serially connected in the output circuit of the first tube, a second pair of inductance elements serially connected and included in the input circuit of the second tube, one inductance of each serially connected pair being coupled to supply signals from the output of the first tube to the input of the second tube, a high conductivity metallic element contained within the other inductance of each of the serially connected pairs, means for simultaneously moving each of the conductive elements within the said inductances for tuning, means for shielding each of the tunable inductance elements one from the other to prevent coupling between said two inductance elements, and a damping resistance means connected in parallel with each of said series combinations of inductance elements.
